UNITED STATES PATENT OFFICE

ALBERT J. KRUSE, OF FREDERICKSBURG, TEXAS

HAY PRESS

Application filed July 17, 1928. Serial No. 293,834.

This invention relates to a press and pertains particularly to a press designed for packing hay into a bundle or bale. The primary object of the present invention is to provide an improved means for imparting an initial movement to a press plunger by the use of a pedal structure which acts as an auxiliary to a hand lever.

In the present type of hay press, the press 10 frame is of elongated rectangular structure mounted horizontally with a plunger arranged in one end and adapted to be moved horizontally from the end of the press box to permit the introduction of additional hay. 15 This plunger is normally manually operated through the medium of a hand lever having pivotal connection with an arm carried by the plunger and considerable difficulty is experienced in starting the initial movement of 20 the lever to get the same in the position where the weight of the operator's body can be applied thereto to force the plunger inwardly. To overcome the difficulty involving the initial movement of the plunger operating 25 lever, the structure embodying the present invention has been developed.

Broadly, the present invention consists in the provision of an auxiliary lever upon which the press operator can step so that 30 the weight of his body will move the plunger inwardly and swing the operating handle to a position where the full weight of the body of the operator can be placed thereon to complete the plunger movement.

The invention will be best understood from a consideration of the following detailed description taken in connection with the accompanying drawings forming part of this specification, with the understanding, however, 40 that the invention is not confined to any strict conformity with the showing of the drawings but may be changed or modified so long as such changes or modifications mark no material departure from the salient features of 45 the invention as expressed in the appended claims.

In the drawings:—

Figure 1 is a central longitudinal sectional view through the forward part of a hay press 50 showing the operating lever structure em-

bodying the present invention in the position assumed when the press plunger is retracted;

Figure 2 is a sectional view taken upon the line 2—2 of Figure 1 looking in the direction of the arrows;

Figure 3 is a sectional view taken upon the line 3—3 of Figure 1;

Figure 4 is a view in side elevation of the nose of the hand lever.

Referring to the drawing in detail where-in like numerals of reference indicate corresponding parts throughout the several views, the numeral 1 indicates a press body of the usual elongated horizontally disposed design having the frame structure 2 at the rear thereof and having a portion of the bottom 3 extended rearwardly a substantial distance and centrally of the body as indicated at 4. This rearwardly extending portion of the bottom of the press is provided at its ends 5 with the upstanding spaced parallel posts 6. 60

Arranged within the press is the usual plunger 6 which carries the rearwardly extending arm 7 which in turn carries a pair of plates 8 arranged against opposite faces thereof and projecting beyond the free end to receive the nose portion 9 of an operating lever 10. The back of the lever 10 adjacent the nose 9 which, as shown, is tapered, has secured thereto the strap plate 11 which extends downwardly and about the nose of the lever, being formed at the nose to provide a bearing 12. This bearing is positioned between the free ends of the plates 8 and receives therethrough the pivot pin 13. 70

Inwardly of the free end of the lever the same, which lies between the posts 5, is mounted to swing upon the pivot pin 14 which is carried by the posts in a plane above the plunger arm 7. The lever 10 is provided at the fulcrum point with the oppositely disposed plates 15, one of which carries a sleeve 16 that extends through the lever body and has connection with the opposite plate. These plates are secured to the lever by bolts 80 or screws or the like so that their displacement will be prevented. The pivot pin 14 which carries the lever 10 is encased in a sleeve 17 which extends through the bearing sleeve 16 and has its ends mounted in the 90

posts 5 in the manner shown. Suitable means such as cotter pins 18 or the like may be employed for preventing longitudinal displacement of the pin 14.

5 Pivottally mounted upon the pivot pin 13, upon each side of the nose of the lever 10 is one end of an arm 19, which arms at their outer ends have secured therebetween the pedal block 20.

10 Each of these arms 19 has pivotally secured thereto adjacent the block 20, a link 21 which is provided with the longitudinally extending slot 22, one end of which extends to a point adjacent the other end of the link.

15 The said other end of each of the links is arranged between the lever 10 and a post 5 and has extending through the slot therein the pin 14 and covering sleeve 17.

The length of the connecting links 21 is 20 such that when the plunger operating lever 10 is swung forwardly to the position where the plunger is fully retracted, the block carrying ends or the treadle of the links 19 will be extended upwardly at an angle of approximately 45°, the nose of the lever and the ends of the plates 8 which are carried by the plunger arm 7 being rearwardly of the posts 5.

When hay is in the press and after the 30 plunger has been retracted for the insertion of more hay and it is desired to start the plunger on its forward movement to compress the same the attendant of the press steps upon the raised block 20 which is carried by 35 the rearwardly extending arms 19, thus causing the arms to swing downwardly in an arc, the inner ends thereof being forced inwardly against the plates 8 as will be readily understood. It will be seen that this downward 40 and forward swinging movement of the arms 19 which constitute an auxiliary lever to the lever 10, will cause the free end or nose of the lever 10 to swing under the pivot pin 14, thus throwing the upper end rearwardly to 45 a point where it will be convenient for the attendant of the press to grasp it and further continue the application of the entire weight of his body to the plunger by swinging and pulling down upon the free end of the lever.

50 The sliding connection of the links 21 over the sleeve 17 permits free forward movement of the arms 19 so that the full sweep of the press lever 10 can be made.

55 From the foregoing description, it will be readily seen that the present auxiliary foot lever will add considerable to the ease of operation of presses of this character and that, therefore, time and effort will be saved 60 in operating the press.

Having thus described my invention what I claim is:—

1. In a press of the character described, a plunger, a swinging initially upwardly extending hand lever connected with the plung-

er for operating the same, and a foot lever adapted when actuated to give initial movement to the plunger and to start the hand lever on its working movement.

2. In a press, a reciprocating plunger, a hand lever connected with said plunger, and a foot lever having pivotal connection at two points with the hand lever, one of said points also connecting with the plunger said foot lever being designed to start the plunger and throw the hand lever to a predetermined position. 70

3. In a press, a reciprocating plunger having an actuating arm, a hand lever pivotally mounted inwardly of one end in a plane above said arm and having pivotal connection at the said end with the arm, and a foot lever having connection with the arm at the point of connection of the hand lever therewith and designed when actuated to give initial movement to the plunger and to throw the hand lever to a predetermined position. 80

4. In a hay press, a plunger having an actuating arm, a pair of standards having said arm extending therebetween, a lever pivotally mounted adjacent one end between said standards in a plane above the arm, pivotal connection between the lever and the arm, a foot lever comprising an elongated body pivotally connected at one end to the arm at the point of connection of the first-mentioned lever therewith, and coupling links between the foot lever adjacent the free end of the same, and said standards. 90

5. In a hay press, a plunger having an actuating arm, a pair of standards having said arm extending therebetween, a lever pivotally mounted adjacent one end between said standards in a plane above the arm, pivotal connection between the lever and the arm, a foot lever comprising an elongated body pivotally connected at one end to the arm at the point of connection of the first-mentioned lever therewith, and coupling links pivotally connected at one end to the foot lever adjacent the free end thereof, and having sliding pivotal connection with the standards to swing about the center about which the first-mentioned lever swings. 100

In testimony whereof I hereunto affix my 115 signature.

ALBERT J. KRUSE.
